United States Patent Office

Des. 217,893

Patented June 30, 1970

217,893

BRASSIERE

Mack Spetnik, Weehawken, N.J., assignor to Maidenform, Inc., New York, N.Y., a corporation of New York

Filed Dec. 31, 1968, Ser. No. 15,156

Term of patent 7 years

Int. Cl. D2—02

U.S. Cl. D2—24

The figure is a front perspective view of a brassiere, showing my new design, the straps are shown broken away for convenience of illustration. The back of the brassiere is conventional.

I claim:

The ornamental design for a brassiere, as shown and described.
